THERMIONIC VALVE APPARATUS

Eric Lawrence Casling White, Hillingdon, England, assignor to Electric & Musical Industries Limited, Hayes, Middlesex, England, a British Company

Application November 28, 1936, Serial No. 113,211
In Great Britain December 4, 1935

5 Claims. (Cl. 175—368)

The present invention relates to pulse-operated thermionic valve apparatus, such for example as frequency dividers, electrical counting arrangements and the like.

5 A frequency divider is known which comprises a condenser arranged in series with the anode-cathode path of a thermionic valve, a resistance and a source of steady potential, the condenser being shunted by a discharge device, such as a 10 neon lamp, of the kind in which a discharge only takes place when the potential between the electrodes is greater than a critical value. Controlling pulses are fed to the control grid of the valve, the arrangement being such that anode current 15 only flows when a pulse is present; the condenser charges up during the time within which anode current is flowing.

In this known arrangement, provided that the controlling pulses are of substantially constant duration and amplitude, it can be arranged that 20 the potential across the condenser does not reach the flash-over potential of the discharge device until a plurality of pulses have been operative on the control grid of the valve; there can accordingly be derived from the terminals of the condenser an oscillation at a frequency which is a 25 sub-multiple of the frequency of the controlling pulses. In such an arrangement, if the duration or amplitude of the controlling pulses is changed, the number of pulses necessary to enable the 30 condenser to charge up sufficiently for the discharge device to flash over changes also, so that the factor of frequency division is dependent upon the duration and amplitude of the controlling pulses.

35 It is an object of the present invention to provide pulse controlled thermionic valve apparatus, such as a frequency divider, an electrical counter or the like, the operation of which is substantially independent of the duration or amplitude 40 of the applied pulses, provided that both the duration and amplitude exceed pre-determined minimum values; thus the pulses may be of varying amplitudes and durations, provided that the 45 duration and amplitude of each pulse are greater than the above-mentioned minima.

It is a further object of the invention to provide pulse-controlled thermionic valve apparatus, the operation of which is substantially independent, over a wide range, of variations in valve 50 characteristics and the potentials of associated sources of current supply.

According to the present invention, apparatus for counting or measuring the frequency of electric pulses comprises means for delivering a

charge on the occurrence of a pulse independently of the amplitude or duration of the pulse to a circuit which for the purpose of counting the pulses integrates the charges, a device for measuring the integrated charge being provided, or for the purpose of measuring the frequency, measures the amount of charge delivered in unit time. Further, according to the invention, apparatus for generating electric pulses at a frequency which is a sub-multiple n of the frequency of applied pulses, comprises means for delivering a charge on the occurrence of a pulse independently of the amplitude or duration of the pulse to a circuit which integrates the charges and generates a pulse after the integration of n pulses and dissipates the integrated charge.

In the case of apparatus for counting according to the invention, a first condenser is charged from a source of current of constant potential, the condenser being discharged in the intervals 20 between pulses and the means for integrating the charges comprises a further condenser and a unilaterally conducting device in the charging path of said first condenser, and a device which is associated with said further condenser is responsive to a predetermined potential value across said further condenser. The first condenser is discharged by a switching device in series with a unilaterally conducting device and the switching device may be a thermionic valve 30 having the pulses to be counted applied between its grid and cathode. The devices associated with the further condenser may consist of an electro-static voltmeter, a thermionic voltmeter, a multi-vibrator or other relaxation oscillator.

In a particular thermionic valve apparatus embodying the invention the switching device is constituted by a pentode valve arranged in shunt with said first condenser. In this arrangement each pulse causes an increment of charge to flow into the second condenser, and it can be arranged that successive increments are substantially equal in magnitude. The charge held by the second condenser, and hence the potential across it, is thus dependent on the number of pulses applied to the switching device, and apparatus according to the invention is thus readily applicable as an electrical counter.

The potential set up across the second condenser may be caused to initiate secondary pulses, each of which represents a plurality of pulses applied to the switching device. The apparatus may thus be employed as a frequency divider. In such an arrangement means are provided for

discharging the second condenser after the plurality of pulses have been applied to it.

In order that the invention may be more clearly understood and readily carried into effect circuit arrangements embodying the invention will now be described by way of example with reference to the accompanying drawings in which:

Fig. 1 shows apparatus according to the invention for use in an electrical counter,

Fig. 2 shows apparatus according to the invention suitable for use as a frequency divider,

Fig. 3 shows an alternative form of frequency divider,

Fig. 4 shows apparatus according to the invention suitable for use for frequency measuring purposes, and

Fig. 5 is an alternative form of frequency measuring circuit.

Referring to Fig. 1, a pentode valve V_1 has its anode and screening grids connected to points at suitable positive potentials in a source of current B_1 , the negative terminal of which is connected to the cathode of the valve V_1 which is earthed. The anode circuit includes a resistance R , the end of which remote from source B_1 is connected to one terminal of a condenser C_1 , the other terminal of which is connected to the cathode of a diode V_2 and the anode of a diode V_3 . The anode of diode V_2 is earthed, and the cathode of diode V_3 is connected through a condenser C_2 to earth, condenser C_2 being shunted by a device X , such as an electrostatic voltmeter or other high impedance indicating device, which is capable of indicating the potential set up across condenser C_2 and hence the number of pulses which has been operative.

The control grid of valve V_1 is arranged, in the absence of pulses, to be at substantially earth potential, and the controlling pulses are applied in negative sense and at such a level as to be capable of swinging the control grid potential to beyond anode current cut-off. A pentode is chosen for V_1 and the anode resistance is made large so that between pulses the anode current flowing is limited by the anode resistance rather than the valve and the anode potential is low compared with the potential at the upper end of the resistance R . When the anode current is cut off by the applied pulses the potential of the anode rises to the potential of the upper end of the resistance R . The more nearly the change of potential of the anode approaches the high tension potential the less is the possible percentage effect of variation in this change caused by a change of valve characteristics. A low impedance triode valve could be used with the large anode resistance but would obviously require a very much greater amplitude of applied pulse to cut off the anode current. In the analysis which follows it is assumed that the anode potential between pulses is so low that the change of anode potential at the occurrence of a pulse is substantially equal to the high tension voltage.

The operation of the arrangement is as follows: assuming condenser C_2 initially to be discharged, on the arrival at the control grid of valve V_1 of a negative pulse of sufficient amplitude, the anode current of V_1 is shut off and the anode potential rises to E_1 , the potential of the source B_1 , in a time determined by the time constant of C_1 and C_2 in series, and R . The negative pulse should last for a time equal at least to a multiple of (say five times) this time constant.

The condensers C_1 and C_2 charge up through

the diode V_3 to the potential E_1 , the potential across C_2 being

$$\frac{C_1}{C_1+C_2} E_1$$

The capacity of C_2 is preferably about 10 to 100 times the capacity of C_1 . 5

At the end of the negative pulse, the potential at the anode of valve V_1 is again brought down nearly to earth potential, due to valve V_1 conducting once more, and C_1 is discharged through V_2 and V_1 in series, the right hand plate of condenser C_1 being brought substantially to earth potential. Condenser C_2 , however, retains its charge, which is increased by a further increment due to the next pulse. The second increment is not quite as big as the first, and causes an increase in potential equal to

$$\frac{C_1}{C_1+C_2} E_1 \times \frac{C_2}{C_1+C_2} 20$$

The increase in potential across condenser C_2 due to the increment of charge resulting from the nth pulse is

$$\frac{C_1 E_1}{C_1+C_2} \times \left(\frac{C_2}{C_1+C_2} \right)^{n-1} 25$$

The potential of condenser C_2 after n increments of charge is

$$\frac{E_1 C_1}{C_1+C_2} \left[1 + \frac{C_2}{C_2+C_1} + \left(\frac{C_2}{C_2+C_1} \right)^2 + \dots + \left(\frac{C_2}{C_2+C_1} \right)^{n-1} \right] = 30$$

$$\frac{E_1 C_1}{C_1+C_2} \times \frac{1 - \left(\frac{C_2}{C_2+C_1} \right)^n}{1 - \frac{C_2}{C_2+C_1}} = E_1 \left\{ 1 - \left(\frac{C_2}{C_2+C_1} \right)^n \right\} 35$$

The number of pulses which have been operative upon valve V_1 can be ascertained by measuring the potential across C_2 , for example with the aid of the electrostatic voltmeter or other high impedance device X . After a given number of pulses, that is, when C_2 has attained a given potential, it may be arranged that the device X operates to discharge C_2 , thus resetting the counter, the device X being arranged at the same time to generate a pulse which may itself be fed to a further counting device. 40 45

The device X may, for this purpose, comprise a neon or other like discharge tube, a grid controlled gas discharge tube, a blocking oscillator or any other known or suitable discharging device. 50

In the arrangement illustrated in Fig. 2, in which the device X includes a multivibrator, the apparatus associated with valves V_1 , V_2 and V_3 is arranged as in Fig. 1. Referring to Fig. 2, the potential differences set up across condenser C_2 are fed to the control grid of a valve V_4 and to the anode of a valve V_5 . The cathode of valve V_4 is connected to an adjustable tapping point in a potential divider comprising resistances R_1 and R_2 in series shunted across source B_1 , the valve V_4 being thus biased so that no anode current flows in valve V_4 until the potential difference across condenser C_2 reaches a pre-determined magnitude. 55 60

A multivibrator comprising valves V_5 and V_6 is provided as shown, valve V_5 being a pentode, the screen grid of which serves as an anode for the purpose of the multivibrator, while its anode-cathode path serves to discharge condenser C_2 . The screening grid of valve V_5 and the anode of valve V_4 are connected through resistance R_4 to a positive terminal in source B_1 . The anode of valve V_6 is connected through bias battery B_2 70 75

to the control grid of valve V_5 and the screening grid of valve V_5 is connected through condenser C_3 to the control grid of valve V_6 ; condenser C_3 is provided with a leak resistance R_3 . During the periods when condenser C_2 is charging up, valve V_5 is biased by battery B_2 so that no anode current flows therein.

The potential of condenser C_2 at which the discharge occurs is close to the potential of the cathode of V_4 , which is equal to

$$\frac{E_1 R_2}{R_2 + R_1}$$

Thus n (the number of increments of charge occurring before C_2 is discharged) is determined by

$$\frac{E_1 R_2}{R_2 + R_1} = E_1 \left[1 - \left(\frac{C_2}{C_2 + C_1} \right)^n \right]$$

Hence

$$\left(\frac{C_2}{C_2 + C_1} \right)^n = \frac{R_1}{R_2 + R_1}, \text{ and } n = \frac{\log \left(1 + \frac{R_2}{R_1} \right)}{\log \left(1 + \frac{C_1}{C_2} \right)}$$

Thus n depends substantially only on the ratios

$$\frac{R_2}{R_1} \text{ and } \frac{C_1}{C_2}$$

and it should be particularly noticed that n is substantially independent of the voltage of the high tension source. Either or both of these ratios may be made variable if desired. The arrangement operates as a frequency divider, pulses of

$$\frac{1}{n}$$

of the frequency of the pulses applied to valve V_1 being set up at the anode of valve V_6 ; this point may if desired be connected to a further counter. The valve V_5 of Fig. 2 may be replaced by two separate valves, which may be triodes, having their grids connected together; the anode of one valve may then be used in the multivibrator circuit and the other may be used for discharging C_2 .

The upper limit to the interval between successive pulses at which counting is satisfactory is set by stray leakage resistances across C_2 , and by attention to the insulation this interval may be made very long. If in a particular application the intervals are short, the battery B_2 may be replaced by a condenser and grid leak of a suitably long time constant.

The length of the pulse which discharges condenser C_2 is set by the time constant of C_3 and R_3 , and is preferably arranged to be less than the minimum interval between the pulses applied to valve V_1 .

An example of a two stage frequency divider embodying blocking oscillators is shown in Fig. 3 in which the valve V'_1 is a blocking oscillator of known type and replaces the valves V_4 , V_5 and V_6 and also acts as the valve corresponding to V_1 in the second counting stage. Diodes V'_2 and V'_3 perform exactly similar functions as the diode valves V_2 and V_3 in the first counting stage which correspond with the similarly lettered valves in Figs. 1 and 2.

Referring now to Fig. 4 of the accompanying drawings, a continuous current meter M is connected across a condenser C_2 in place of the intermittently conductive device. The reading of the meter M is directly proportional to the frequency of the applied pulses and dependent upon the supply voltage from the battery B . As in the

case of a circuit for pulse counting, it is assumed that in the arrangement of Fig. 3 the amplitude of the applied pulses is sufficient to produce anode current cut off in the valve V_1 .

Fig. 5 illustrates the application of contact rectifiers in a bridge circuit to a frequency measuring circuit embodying the invention. The use of such a rectifier provides twice the amount of current to be passed to the meter M than in the case of the diode connections shown in the previous figures. It will be seen that in this figure there is no condenser equivalent to C_2 in the preceding figures, although such a condenser may be connected across the meter M .

It will be understood that while particular applications of the invention have been described and illustrated in detail the invention may find application in numerous circuits not specifically described, thus for example, although the switching device in the circuits described takes the form of a thermionic valve, a mechanically operated switch or relay may be employed.

I claim:

1. In combination, a storage condenser, a charging condenser, a unilaterally conducting device connected between one plate of each of said condensers for admitting current from said charging condenser to said storage condenser, a second unilaterally conducting device connected between the junction of the charging condenser and the first-mentioned conducting device and the other plate of said storage condenser for discharging said charging condenser, means to impress a pulsating current between said other plate of the storage condenser and the other plate of the charging condenser, and a loading impedance across the storage condenser for discharging the storage condenser following a predetermined charge on said storage condenser.

2. Apparatus as claimed in claim 1 wherein said unilaterally conducting devices comprise electron discharge tubes each having a cathode and anode.

3. Apparatus for frequency division comprising a storage condenser, a resistor, a voltage source between one plate of said storage condenser and said resistor to apply a negative voltage to said plate, a charging condenser, one plate of which is connected to the end of said resistor remote from said voltage source, a unilaterally conducting device connected between the other plate of said charging condenser and the other plate of said storage condenser for charging said storage condenser, a switching device responsive to controlling impulses connected between the junction of the resistor and the first-mentioned plate of said storage condenser, a second unilaterally conducting device connected between the junction of the charging condenser and the first said unilaterally conducting device and the said other plate of the storage condenser for discharging said charging condenser, and a loading impedance across the storage condenser for discharging the storage condenser following a predetermined charge on said storage condenser.

4. Apparatus for indicating electric pulses comprising a storage condenser, a rectifier having an anode and a cathode, said cathode being connected to one plate of said storage condenser, a resistor, a charging condenser connected between said resistor and the anode of said rectifier, a voltage source connected between the other plate of said storage condenser and the end of said resistor remote from the charging condenser to apply a negative voltage to said other plate of the

storage condenser, a switching device responsive to controlling impulses connected between the junction of the resistor and said charging condenser and said other plate of the storage condenser, a unilaterally conducting device between the anode of said rectifier and said other plate of the storage condenser for discharging said second condenser, and a loading impedance across the storage condenser for discharging the storage

condenser following a predetermined charge on said storage condenser.

5. Apparatus as claimed in claim 4 wherein the said switching device comprises a thermionic valve having at least a grid, cathode and anode, the pulses being applied in a negative sense between the grid and cathode. 5
